(57) **CLAIM**

The ornamental design for a box opening device as shown and described.

DESCRIPTION

FIG. 1 is a front perspective view of a box opening device according to the present invention.

FIG. 2 is a front elevation view of the box opening device illustrated in FIG. 1.

FIG. 3 is a rear elevation view of the box opening device illustrated in FIG. 1.

FIG. 4 is a side elevation view of the box opening device illustrated in FIG. 1.

FIG. 5 is another side elevation view of the box opening device illustrated in FIG. 1.

FIG. 6 is a top plan view of the box opening device illustrated in FIG. 1; and,

FIG. 7 is a bottom plan view of the box opening device illustrated in FIG. 1.
